[57]

ABSTRACT

A water containing fire extinguishing foam concentrate comprises an active ingredient about 1% to 10% by weight of a compound of the general formula

wherein a is a number of between one and three inclusive, X is hydrogen or Y and Y is a hydrophilating group such as polyethyleneglykol or an aminoxyd or ammoniumsalt containing group.

The concentrate may also contain solubilizing agents.

7 Claims, No Drawings

FIRE EXTINGUISHING FOAM CONCENTRATE
COMPRISING AN ORGANIC FLUORINE COMPOUND
AND A SOLUBILIZING AGENT

FIELD OF INVENTION

The invention relates to fire extinguishing foam concentrates which contain water and an organic fluor compound.

BACKGROUND INFORMATION AND PRIOR ART

As is generally known, fires, particularly fires of fuels and propellants, are combatted by spraying foam in the form of continuous coats or coverings. Such foam blankets are also suitable for preventing the initial formation of fires.

Suitable prior art foaming agents for such purposes are prepared from protein salts, as for example from keratins, albumins, seed flour and the like which are modified by hydrolysis and stabilized with certain preselected metal salts.

However, as is wellknown in the art, foaming agents produced from protein hydrolysates cannot successfully be used for the combatting of certain types of fires. Thus, for example, such foaming agents are not suitable for fighting fuel fires or fires of polar substances as, for example, alcohol fires.

A further drawback of these known foaming agents resides in the fact that they are incompatible with dry fire extinguishing powders which are customarily used simultaneously, particularly if the powders have silicon containing surfaces. If such prior art foaming agents are used in conjunction with dry fire extinguishing powders, the foam has a tendency to collapse.

It has recently been suggested to employ foaming agents which are water soluble, ion-active derivatives of a fluorocarbon- or a fluorosulfonic acid. Such compounds are usually applied in the form of an aqueous master solution. Concentrates of this kind have been described, for example, in German Pat. No. 1,216,116. However, also the latter type of prior art foaming agents is not fully satisfactory.

Thus, for example, the prior art fluorocarbon-tensides do not readily form stable aqueous foams of high expansion rate.

Accordingly, it is an object of the present invention to provide a foaming agent or concentrate of the indicated kind which has superior expansion rate properties as compared to the prior art compounds and which forms stable, aqueous foams.

Generally it is an object of this invention to improve on the art of fire extinguishing foam concentrates as presently practiced.

SUMMARY OF THE INVENTION

In accordance with this invention it has surprisingly been found that another class of organic fluor compounds than that disclosed in German Pat. No. 1,216,116 exhibits particularly favorable operational characteristics when used as the active ingredient in fire extinguishing foams and that the above objects are fully attained with such other organic fluor compounds and that such other organic fluor compounds are superior in respect to their fire combatting properties if compared with the known compounds.

The inventive fire extinguishing foam concentrate is characterized in that it comprises about 1 to 10% by weight of compounds of the general formula

wherein

a is a number having the value of from one to three inclusive
X is hydrogen or Y and

Y stands for a hydrophilating group, particularly polyethyleneglykol or a group containing an aminoxyd or ammoniumsalt group. The concentrate may advantageously contain a sufficient amount of a solubilizing agent in order to render the concentrate water soluble.

The particularly favorable operational characteristics of the inventive fire extinguishing foam concentrate are primarily caused by the hydrophobic moiety of the active substances contained in the concentrate. The solubilizing group is accordingly of lesser importance. Some of the compounds embraced by the above general formula have proved to be particularly effective for the inventive purposes. Accordingly, fire extinguishing foam concentrates are particularly preferred wherein the active ingredient corresponds to a compound having the general formula

15 wherein

$b = 2$ or 3 , or to the general formula

25 wherein c and d each have a value of from 0 to 50, while the sum of $c + d = 1$ to 50.

It is desirable but not necessary that the fluororganic compounds contained in the concentrate are water soluble. In the event that they are soluble with difficulty only or are substantially insoluble, they may be converted into water miscible form by the addition of a solubilizing agent of a nature known per se. Various solubilizing agents may be used for this purpose. Thus, for example, triethanolammoniumlaurylsulfate, triethanolammonium dodecylbenzenesulfonate as well as the various ionogenic and nonionogenic tensides with HLB values above 12 are suitable for the indicated purpose.

30 The operational characteristics of the fluor compounds used in the inventive fire extinguishing foam concentrate may in some instances be favorably influenced by the addition of preselected solubilizing agents. For this purpose the addition of water soluble polysiloxanes has proved to be particularly favorable. Such water soluble polysiloxanes, acting as solubilizing agents for the inventive purposes, are, for example, polysiloxane-polyalkyleneglykol-mixed block-copolymers as well as polysiloxanes which contain ionogenic groups linked to SiC, for example, organofunctional sulfates of polysiloxanes as disclosed, for example, in German Pat. No. 1,179,937.

35 Experiments have indicated that solubilizing agents of the following formula are particularly suitable

40 In formula I,
 R stands for trimethylsilyl.

Within a compound mixture, up to 50 mole % of trimethylsilyl may be replaced by alkyl, preferably lower alkyl.

R^1 is aryl or alkyl.

If R^1 stands for aryl, then phenyl is the preferred aryl group. By contrast, if R^1 is alkyl, the preferred alkyl group is methyl. Another preferred alkyl group is tri- $\gamma\gamma\gamma$ -trifluoropropyl.

45 55 60 65 70 The meaning of the symbol R^1 may be different within the same siloxane group. For example, in addition to the preferred methyl groups, some phenyl groups or trifluoropropyl groups may be present. The group R^1 , moreover, may be trimethylsiloxyl.

n stands for zero or one.

If $n = 1$, then the organosilicon compound is comprised of a sulfate group which is linked to the siloxane group through a carbon bridge. However, if $n = 0$ then the organosilicon compound is a sulfonate.

75 70 75 75 75 m has a value of from one to three, preferably one to 1.3.

p, *q*, and *r* indicate the number of ethylenoxide units in the amine and have a value of from 0 to seven. The sum of *p*, *q* and *r* is one through 20.

Such compounds may be produced, for example, according to the process disclosed in German Patent 1,179,937.

A compound embraced by the above formula I has been proved to be particularly suitable for the inventive purposes wherein *R* is trimethylsilyl, *n* and *m* are equal to one and *p*, *q* and *r* are each 2.4. *R'* stands for methyl. This latter compound is preferably added to the fire extinguishing foam concentrate in an amount corresponding to three to 15 times the amount in weight of the fluoro compound. Mixtures, which contain this substance as solubilizing agent, may also be used with hard or sea water to form stable, firecombatting foams. This is an important advantage particularly considering the fact that the presently available fluorocarbontesides cannot be foamed with sea water.

Also suitable as solubilizing agents are nonionogenic siloxanetensides of the following general formula

In this formula the symbols *R*, *R*¹ and *m* have the same meaning as indicated above.

*R*² is hydrogen, alkyl or aryl.

If *R*² is aryl then phenyl is the preferred group; if *R*² is alkyl, lower alkyl is preferred.

M stands for

or the group

40

In the latter group, *t* has a value of from one to three. *u* has a value of from seven through 30.

The above organosilicon solubilizing agents have the particular advantage that they contribute not only to the solubilization but also significantly contribute to the formation of an effective fire extinguishing foam proper.

The advantageous operational characteristics of the inventive fire extinguishing foam concentrates will become clearly apparent in considering and evaluating the following examples.

In order to test the expansion rate and foam stability the so-called foam impact test was used. A detailed description of the impact foam test is contained, for example, in the book by E. 15 Manegold: Schaum, Strassenbau, Chemie und Technik-verlagsgesellschaft m.b.H., Heidelberg, 1953, pages 97 and 98. In performing the test, a measuring cylinder with a diameter of 5.4 cm. was used. The disc, used for the impact foam test, had a diameter of 5 cm. and contained 87 holes with a diameter of 20 1 mm. for each hole. The material to be foamed was filled into the measuring cylinder to a level of 3 cm. and was thereafter foamed by moving the disc up and down for 40 times. The results which were obtained are tabulated in the following Tables Ia - Ic.

25 The abbreviation HVT in the Table stands for half value time and indicates the time period which passed until an amount of liquid had been reformed which corresponded to one half of the original amount. The height of the foam was measured in millimeters.

30 The foam which was produced according to this foam impact method in tap water of about 10° German hardness was also used for extinguishing gasoline, supergasoline and butanol fires. For this purpose 100 ccm. of these liquids were in each case fed to a pot of 14.5 cm. diameter. The liquids were then ignited and after a burning time of 2 minutes the extinguishing or fire combatting procedure was initiated. The results are tabulated in Tables IIa 1 to IIa 3, IIb 1 to IIb 3 and IIc 1 to IIc 3.

¹ Fire is not extinguished.
The value for a 15 second extinction time was extrapolated were necessary.
⁺No corresponding value could be extrapolated. The amount of concentrate is calculated for extinction time of 5 seconds.

What is claimed is:

1. In a fire extinguishing water containing foam concentrate, the improvement which comprises that its active ingredient is about 1 to 10% by weight of a compound of the formula

wherein,

a is a number having a value of from one to three inclusive,
X is hydrogen or Y and

Y is a hydrophilating group;
said concentrate additionally containing a solubilizing agent in an amount sufficient to render the concentrate water soluble, said solubilizing agent having an h_{1b} value above 12.

2. The improvement of claim 1, wherein said solubilizing agent is triethanol ammonium laurylsulfate, triethanol ammonium dodecyl benzene sulfonate, an ionogenic tenside or a non-ionogenic tenside.

3. The improvement as claimed in claim 1, wherein the hydrophilating group Y is polyethyleneglykol or a group containing aminoxyde or ammoniumsalt.

4. The improvement as claimed in claim 1, wherein the active ingredient corresponds to the formula

wherein $b = 2$ or 3.

5. The improvement as claimed in claim 1, wherein the active ingredient is a compound of the general formula

wherein $b = 2$ or 3 and c and d are each numbers having a value of from to 50, the sum of $c+d = 1$ to 50.

6. The improvement as claimed in claim 1, wherein the solubilizing agent is a water soluble polysiloxane.

7. The improvement as claimed in claim 6, wherein the polysiloxane is a compound of the formula

said agent being contained in the concentrate in an amount by weight corresponding to three to 15 times the quantity of said active ingredient.
